UNITED STATES PATENT OFFICE.

CHARLES A. ABBATH, OF QUINCY, ILLINOIS.

CABINET.

1,094,397.

Specification of Letters Patent. Patented Apr. 21, 1914.

Application filed August 23, 1913. Serial No. 786,247.

To all whom it may concern:

Be it known that I, CHARLES A. ABBATH, a citizen of the United States, and a resident of the city of Quincy, county of Adams, 5 and State of Illinois, have invented certain new and useful Improvements in Cabinets, of which the following is a specification.

My invention relates to improvements in cabinets and has for its object the provision 10 of an improved cabinet which is so arranged and constructed as to permit of the ready sub-division of compartments therein and thus permit of ready rearrangement of articles therein.

15 The invention consists in the combinations and arrangements of parts hereinafter described and claimed.

The invention will be best understood by reference to the accompanying drawing 20 forming a part of this specification, and in which—

Figure 1 is a front elevation of a cabinet embodying my invention, and Fig. 2, a perspective view of a shiftable shelf and its 25 supports mounted in the construction.

The preferred form of construction as illustrated in the drawing comprises a cabinet which is made of wood or other suitable material and is provided with a plurality of 30 horizontal fixed shelves 1 and vertical partitions 2 dividing the same into a plurality of compartments 3 of equal sizes. A number of shiftable shelves 4 are arranged to be shifted to different compartments in the 35 cabinet. Each of these shelves 4 is provided with grooves 5 in its edges and two sheet metal supporting plates 6 having central ribs 7 adapted to fit the corresponding grooves 5 are provided for each of the 40 shelves 4. These plates 6 are of a size to fit within the compartments and are arranged on edge on each side thereof with their lips 7 extending inwardly. When in this position shiftable shelf 4 may be readily slid 45 into or out of position as will be readily

understood. By this arrangement it will be observed that any of the compartments may be readily sub-divided by shelf 4 thus permitting of the rearrangement of the articles in the cabinet as indicated in Fig. 1 when 50 desired.

While I have illustrated and described the preferred form of construction for carrying my invention into effect, this is capable 55 of variation and modification without departing from the spirit of the invention. I, therefore, do not wish to be limited to the precise details of construction set forth, but desire to avail myself of such variations and modifications as come within the scope of 60 the appended claims.

Having described my invention what I claim as new and desire to secure by Letters Patent is:

1. A cabinet comprising a plurality of compartments; a shiftable shelf; and two shiftable supports adapted to fit within said compartments, each of said supports consisting of a plate adapted to rest upon the bottom of the compartment and provided with a 70 rib adapted to serve as a support for the corresponding edge of said shelf, substantially as described.

2. A cabinet composing a plurality of compartments of equal sizes; a shiftable 75 shelf having grooved edges; and two shiftable supports adapted to fit within any of said compartments, each of said supports consisting of a sheet metal plate provided with a central rib adapted to fit the groove 80 in the corresponding edge of said shelf, substantially as described.

In testimony whereof I have signed my name to this specification in the presence of two subscribing witnesses.

CHARLES A. ABBATH.
